MOLDED CASING

Walter W. Schroeder, Williamstown, Mass.
Application June 24, 1958, Serial No. 51,508

Term of patent 14 years

(Cl. D26—1)

FIG. 1

FIG. 2

FIG. 3

FIG. 4

Fig. 1 is a perspective view of a molded casing showing my new design;

Fig. 2 is an opposite perspective view;

Fig. 3 is an end elevational view; and

Fig. 4 is an opposite end elevational view thereof.

The dominant features of my new design are shown in solid lines in the drawing.

I claim:

The ornamental design for a molded casing, as shown and described.

UNITED STATES PATENT OFFICE
CERTIFICATE OF CORRECTION

Design No. 185,959

August 25, 1959

Walter W. Schroeder

It is hereby certified that error appears in the above numbered patent requiring correction and that the said Letters Patent should read as corrected below.

In the grant, lines 1 to 3, for "Walter W. Schroeder, of Williamstown, Massachusetts," read -- Walter W. Schroeder, of Williams- town, Massachusetts, assignor to Sprague Electric Company, of North Adams, Massachusetts, a corporation of Massachusetts, --; line 13, for "Walter W. Schroeder, his heirs" read -- Sprague Electric Company, its successors --; in the heading to the drawings and printed specification, line 3, for "Walter W. Schroeder, Williamstown, Mass." read -- Walter W. Schroeder, Williamstown, Mass., assignor to Sprague Electric Company, North Adams, Mass., a corporation of Massachusetts --.

Signed and sealed this 29th day of March 1960.
